ABSTRACT

A reference buffer circuit provides a reference voltage at an output node and comprises a closed-loop branch comprising an amplifier and first and second MOS transistors and an open-loop branch comprising a third MOS transistor. A positive input terminal of the amplifier receives an input voltage. A gate of the first MOS transistor is coupled to the output terminal of the amplifier, and a source is coupled to a negative input terminal of the amplifier. A gate of the second MOS transistor is coupled to the drain of the first MOS transistor, a source is coupled to a first voltage source, and a drain is coupled to the source of the first MOS transistor. A gate of the third MOS transistor is coupled to the output terminal of the amplifier, and a source is coupled to the output node.

REFERENCE BUFFER CIRCUITS FOR PROVIDING REFERENCE VOLTAGES

BACKGROUND OF THE INVENTION

1. Field of the Invention

The invention relates to a reference buffer circuit, and more particularly to a reference buffer circuit for providing at least one reference voltage to an analog-to-digital converter, regulator or the like.

2. Description of the Related Art

Reference buffer circuits are required for high-speed and high-resolution analog-to-digital converters (ADCs). A reference buffer circuit usually comprises a reference buffer and provides at least one reference voltage to an ADC. There are two types of reference buffer circuits available for ADCs: closed-loop reference buffer circuits and open-loop reference buffer circuits.

FIG. 1 shows a conventional closed-loop reference buffer circuit 1. An amplifier 10 has a negative feedback loop. The amplifier 10 receives an input voltage V_{ref_in} at a positive input terminal and outputs a reference voltage V_{ref} . The output impedance of the reference buffer circuit 1 is equal to $R_{OUT}/(1+A)$, wherein R_{OUT} represents the output impedance of the amplifier 10, and A represents the gain thereof. When the reference buffer circuit 1 operates at a high frequency, the output impedance of the reference buffer circuit 1 is required to be low enough to rapidly stabilize the reference voltage V_{ref} . However, the wide bandwidth causes the power consumption and noise of the reference buffer circuit 1 to be increased. It is difficult to design an internal closed-loop reference buffer circuit for a high-resolution ADC.

FIG. 2 shows a conventional single-ended open-loop reference buffer circuit. A single-ended open-loop reference buffer circuit 2 comprises an amplifier 20, N-type metal oxide semiconductor (NMOS) transistors 21 and 22, and load units 23 and 24. The operation of the NMOS transistor 22 is similar to the NMOS transistor 21. The amplifier 20 and the NMOS transistor 21 form a negative feedback loop, while the NMOS transistor 22 is disposed in an open-loop circuit. In steady state, reference voltage V_{ref} tracks reference voltage V_{refx} . Moreover, the output impedance of the open-loop reference buffer circuit 2 is equal to $1/gm$, wherein gm represents the transconductance of the NMOS transistor 22, and the bandwidth of the amplifier 20 can be narrower, the power consumption of the open-loop reference buffer circuit 2 is less than that of the closed-loop reference buffer circuit 1 as illustrated in FIG. 1.

FIG. 3 shows a conventional differential open-loop reference buffer circuit. A differential open-loop reference buffer circuit 3 comprises amplifiers 30 and 31, NMOS transistors 32 and 33, P-type metal oxide semiconductor (PMOS) transistors 34 and 35, and resistors 36 and 37. Positive input terminals of the amplifiers 30 and 31 respectively receive input voltages V_{refp_in} and V_{refn_in} . The amplifier 30 and the NMOS transistor 32 form one negative feedback loop, and the amplifier 31 and the PMOS transistor 34 form the other negative feedback loop. The NMOS transistor 33 is disposed in one open-loop circuit, and the PMOS transistor 35 is disposed in the other open-loop circuit. In steady state, reference voltages V_{refp} and V_{refn} respectively track reference voltages V_{refpx} and V_{refnx} .

In FIG. 2, there is a voltage difference between the gate and the source of each of the NMOS transistors 21 and 22 which are both operated in saturation region, and the voltage of an output terminal of the amplifier 20 is larger than the reference voltage V_{refx} by the voltage difference, so that a required

supply voltage of the open-loop reference buffer circuit 2 is large. If the open-loop reference buffer circuit 2 operates under a low supply voltage due to design requirements, the maximum value of the reference voltage V_{ref} is suppressed to be small. Similarly, in FIG. 3, there is a voltage difference between the gate and the source of each of the NMOS transistors 32 and 33 and there is a voltage difference between the gate and the source of each of the PMOS transistors 34 and 35, and the maximum value of the reference voltage V_{refp} and the minimum values of the reference voltage V_{refn} are limited when the open-loop reference buffer circuit 3 operates under a low supply voltage, so that the swing between the reference voltages V_{refp} and V_{refn} is hard to meet design requirements.

With the advancement of semiconductor processes, the operation voltage of semiconductor decreases. Thus, a reference buffer circuit, which can operate under low supply voltage, can provide reference voltages with large swing, and has less power consumption and high operation speed, is required.

BRIEF SUMMARY OF THE INVENTION

An exemplary embodiment of reference buffer circuit provides a reference voltage at an output node and comprises a closed-loop branch and an open-loop branch. The closed-loop branch comprises an amplifier, a first metal oxide semiconductor (MOS) transistor, and a second MOS transistor, and the open-loop branch comprises a third MOS transistor. A positive input terminal of the amplifier receives an input voltage. A gate of the first MOS transistor is coupled to the output terminal of the amplifier, and a source thereof is coupled to a negative input terminal of the amplifier. A gate of the second MOS transistor is coupled to the drain of the first MOS transistor, a source thereof is coupled to a first voltage source, and a drain thereof is coupled to the source of the first MOS transistor. A gate of the third MOS transistor is coupled to the output terminal of the amplifier, and a source is coupled to the output node.

Another exemplary embodiment of reference buffer circuit provides reference buffer circuit and comprises a closed-loop branch and an open-loop branch. The closed-loop branch comprises an amplifier, a source-follower transistor, and a first current transistor, and the open-loop branch comprises a driving transistor and a second current transistor. The amplifier receives an input voltage. A gate of the source-follower transistor is coupled to an output of the amplifier, and a first terminal thereof is coupled to a negative input terminal of the amplifier. The first current transistor is coupled to the first terminal of the source-follower transistor in series and has a gate coupled to a second terminal of the source-follower transistor. A gate of the driving transistor is coupled to the output terminal of the amplifier, and a first terminal thereof provides a reference voltage. The second current transistor is coupled to the first terminal of the driving transistor in series and has a gate coupled to a second terminal of the driving transistor.

Another exemplary embodiment of reference buffer circuit provides a first reference voltage at a first output node and a second reference voltage at a second output node and comprises a closed-loop branch and an open-loop branch. The closed-loop branch comprises a first amplifier, a second amplifier, a first metal oxide semiconductor (MOS) transistor, a second MOS transistor, and a third MOS transistor. The open-loop branch comprises a fourth MOS transistor and a fifth MOS transistor.

In the closed-loop branch, a positive input terminal of the first amplifier receives a first input voltage, and a positive input terminal of the second amplifier receives a second input voltage. A gate of the MOS transistor is coupled to the output terminal of the first amplifier, and a source thereof is coupled to the negative input terminal of the amplifier. A gate of the second MOS transistor is coupled to the output terminal of the second amplifier, a source thereof is coupled to the negative input terminal of the amplifier, and a drain thereof is coupled to the drain of the first MOS transistor. A gate of the third MOS transistor is coupled to the drain of the second MOS transistor, a source thereof is coupled to the first voltage source, and a drain thereof is coupled to the source of the second MOS transistor. The third MOS transistor is coupled between a first voltage source and the second MOS transistor.

In the open-loop branch, a gate of the fourth MOS transistor is coupled to the output terminal of the first amplifier, and a source thereof is coupled to the first output node. A gate of the fifth MOS transistor is coupled to the output terminal of the second amplifier, a source thereof is coupled to the second output node, and a drain thereof is coupled to the drain of the fourth MOS transistor.

Another exemplary embodiment of reference buffer circuit provides reference buffer circuit and comprises a closed-loop branch and an open-loop branch. The closed-loop branch comprises a first amplifier, a second amplifier, first and second source-follower transistors, and a first current transistor. The open-loop branch comprises first and second driving transistors and a second current transistor.

In the closed-loop branch, the first amplifier receives a first input voltage, and the second amplifier receives a second input voltage. A gate of the first source-follower transistor is coupled to an output terminal of the first amplifier, and a first terminal thereof is coupled to a negative input terminal of the amplifier. A gate of the second source-follower transistor is coupled to the output terminal of the second amplifier, and a first terminal thereof is coupled to the negative input terminal of the second amplifier, and a second terminal thereof is coupled to a second terminal of the first source-follower MOS transistor. The first current transistor is coupled to the first terminal of the second source-follower transistor in series and has a gate coupled to the second terminal of the second source-follower MOS transistor.

In the open-loop branch, a gate of the first driving transistor is coupled to the output terminal of the first amplifier, and a first terminal thereof provides a first reference voltage. A gate of the second driving transistor is coupled to the output terminal of the second amplifier, a first terminal thereof provides a second reference voltage, and a second terminal thereof is coupled to a second terminal of the first current MOS transistor. The second current transistor is coupled to the first terminal of the second driving transistor in series and has a gate coupled to the second terminal of the second driving MOS transistor.

A detailed description is given in the following embodiments with reference to the accompanying drawings.

BRIEF DESCRIPTION OF THE DRAWINGS

The invention can be more fully understood by reading the subsequent detailed description and examples with references made to the accompanying drawings, wherein:

FIG. 1 shows a conventional basic closed-loop reference buffer circuit;

FIG. 2 shows a conventional single-ended open-loop reference buffer circuit;

FIG. 3 shows a conventional differential open-loop reference buffer circuit;

FIG. 4 shows an exemplary embodiment of a reference buffer circuit;

FIG. 5 shows another exemplary embodiment of a single-ended reference buffer circuit;

FIG. 6 shows an exemplary embodiment of a differential reference buffer circuit; and

FIG. 7 shows another exemplary embodiment of a differential reference buffer circuit.

DETAILED DESCRIPTION OF THE INVENTION

The following description is of the best-contemplated mode of carrying out the invention. This description is made for the purpose of illustrating the general principles of the invention and should not be taken in a limiting sense. The scope of the invention is best determined by reference to the appended claims.

In an exemplary embodiment of a reference buffer circuit in FIG. 4, a single-ended reference buffer circuit 4 generates a reference voltage V_{refp} at an output node N_{out} and comprises an amplifier 40, a P-type metal oxide semiconductor (PMOS) source-follower transistor 41, a PMOS driving transistor 43, PMOS current transistors 42 and 44, and load units 45 and 46. That is, in the single-ended reference buffer circuit 4, a closed-loop branch B40 comprises the amplifier 40, the PMOS transistors 41 and 42, and the load unit 45, and an open-loop branch B41 comprises the PMOS transistors 43 and 44 and the load unit 46.

In the closed-loop branch B40, a positive input terminal IN_+ of the amplifier 40 receives an input voltage V_{refp_in} . A gate of the PMOS transistor 41 is coupled to an output terminal OUT of the amplifier 40, and a source of the PMOS transistor 41 is coupled to a negative input terminal IN_- of the amplifier 40. A gate of the PMOS transistor 42 is coupled to a drain of the PMOS transistor 41, a source of the PMOS transistor 42 is coupled to a supply voltage source VDD , and a drain of the PMOS transistor 42 is coupled to the source of the PMOS transistor 41. The load unit 45 is coupled between the drain of the PMOS transistor 41 and a low voltage source, such as signal ground GND .

In the open-loop branch B41, a gate of the PMOS transistor 43 is coupled to the output terminal OUT of the amplifier 40, and a source of the PMOS transistor 43 is coupled to the output node N_{out} . A gate of the PMOS transistor 44 is coupled to the drain of the PMOS transistor 43, a source of the PMOS transistor 44 is coupled to the supply voltage source VDD , and a drain of the PMOS transistor 44 is coupled to the output node N_{out} . The load unit 46 is coupled between the drain of the PMOS transistor 43 and the signal ground GND .

While operating, a current I_{40} and a reference voltage V_{refpx} are generated in the closed-loop branch B40, and a current I_{41} and a reference voltage V_{refp} are generated in the open-loop branch B41. The current I_{41} is typically N times the current I_{40} for ensuring the driving ability of the reference buffer circuit 4. Thus, the size of the PMOS transistor 43 is N times the size of the PMOS transistor 41, and the size of the PMOS transistor 44 is N times the size of the PMOS transistor 42. The impedance of the load unit 45 is N times the impedance of the load unit 46. In this embodiment, the size of each transistor can be a respective width-length ratio (W/L). Moreover, the load units 45 and 46 can be implemented by transistors or resistors. For example, if the load units 45 and 46 are implemented by resistors, the resistance value of the load unit 45 is N times the resistance value of the load unit 46. If the load units 45 and 46 are implemented by transistors, the size

60 of 65

of the load unit **46** is N times the size of the load unit **45**. According to above circuit structure, the reference voltage Vrefp tracks the reference voltage Vrefpx, and the PMOS current transistors **42** and **44** act as current sources.

In the embodiment of FIG. 4, the maximum value of the reference voltage Vrefp is equal to about $(vdd - |vds|)$, wherein vdd represents the voltage value provided by the supply voltage source VDD, and vds represents the voltage difference between the drain and the source of the PMOS transistor **44**. The reference voltage Vrefp is not limited by the voltage difference between the gate and the source of the PMOS transistor **41** or **43**, which is operated in saturation region and coupled to the output terminal OUT of the amplifier **40**, and the reference buffer circuit **4** therefore can normally operate even under a very low supply voltage provided by the supply voltage source VDD. Moreover, the output impedance of the reference buffer circuit **4** is substantially equal to $1/gm$ so as to rapidly stabilize the reference voltage Vrefp, and the bandwidth of the amplifier **40** is not so required, therefore, the power consumption of the reference buffer circuit **4** can be more decreased.

FIG. 5 shows another exemplary embodiment of a single-ended reference buffer circuit. A single-ended reference buffer circuit **5** generates a reference voltage Vrefn at an output node Nout and comprises an amplifier **50**, an NMOS source-follower transistor **51**, an NMOS driving transistor **53**, NMOS current transistors **52** and **54**, and load units **55** and **56**. That is, in the single-ended reference buffer circuit **5**, a closed-loop branch **B50** comprises the amplifier **50**, the NMOS transistors **51** and **52**, and the load unit **55**, and an open-loop branch **B51** comprises the NMOS transistors **53** and **54** and the load unit **56**. A source of the NMOS transistor **53** is coupled to a drain of the NMOS transistor **54** at the output node Nout. While operating, a current **I50** and a reference voltage Vrefnx are generated in the closed-loop branch **B50**, and a current **I51** and a reference voltage Vrefn are generated in the open-loop branch **B51**. The current **I51** is typically N times the current **I50** for ensuring the driving ability of the reference buffer circuit **5**. Thus, the size of the PMOS transistor **53** is N times the size of the PMOS transistor **51**, and the size of the PMOS transistor **54** is N times the size of the PMOS transistor **52**. The impedance of the load unit **55** is N times the impedance of the load unit **56**. In this embodiment, the size of each transistor can be a respective width-length ratio (W/L). Moreover, the load units **55** and **56** can be implemented by transistors or resistors. For example, if the load units **55** and **56** are implemented by resistors, the resistance value of the load unit **55** is N times the resistance value of the load unit **56**. If the load units **55** and **56** are implemented by transistors, the size of the load unit **56** is N times the size of the load unit **55**. According to above circuit structure, the reference voltage Vrefn tracks the reference voltage Vrefnx, and the NMOS current transistors **52** and **54** act as current sinks.

In the embodiment of FIG. 5, the minimum value of the reference voltage Vrefn is equal to about $|vds|$, wherein vds represents the voltage difference between the drain and the source of the NMOS transistor **54**. The reference voltage Vrefn is not limited by the voltage difference between the gate and the source of the NMOS transistor **51** or **53**, which is operated in saturation region and coupled to the output terminal OUT of the amplifier **50**, and the reference buffer circuit **5** therefore can normally operate even under a very low supply voltage provided by the supply voltage source VDD. Moreover, the output impedance of the reference buffer circuit **5** is substantially equal to $1/gm$ so as to rapidly stabilize the reference voltage Vrefn, and the bandwidth of the ampli-

fier **50** is not so required, therefore, the power consumption of the reference buffer circuit **5** can be more decreased.

FIG. 6 shows an exemplary embodiment of a differential reference buffer circuit. A differential reference buffer circuit **6** generates reference voltages Vrefp and Vrefn respectively at output nodes Noutp and Noutn and comprises amplifiers **60** and **61**, a PMOS source-follower transistor **62**, a PMOS driving transistor **63**, an NMOS source-follower transistor **64**, an NMOS driving transistor **66**, NMOS current transistors **65** and **67**, and current sources **68** and **69**. That is, in the differential reference buffer circuit **6**, a closed-loop branch **B60** comprises the amplifiers **60** and **61**, the PMOS transistor **62**, the NMOS transistors **64** and **65**, and the current source **68**, and an open-loop branch **B61** comprises the PMOS transistor **63**, the NMOS transistors **66** and **67**, and the current source **69**.

In the closed-loop branch **B60**, a positive input terminal IN+ of the amplifier **60** receives an input voltage Vrefp_in, and a positive input terminal IN+ of the amplifier **61** receives an input voltage Vrefn_in. A gate of the PMOS transistor **62** is coupled to an output terminal OUT of the amplifier **60**, and a source of the PMOS transistor **62** is coupled to a negative input terminal IN- of the amplifier **60**. A gate of the NMOS transistor **64** is coupled to an output terminal OUT of the amplifier **61**, a source thereof is coupled to a negative input terminal IN- of the amplifier **61**, and a drain of the NMOS transistor **64** is coupled to a drain of the PMOS transistor **62**. A gate of the NMOS transistor **65** is coupled to the drain of the NMOS transistor **64**, a source of the NMOS transistor **65** is coupled to a low voltage source, such as signal ground GND, and a drain of the NMOS transistor **65** is coupled to the source of the NMOS transistor **64**. The current source **68** is coupled between the source of the PMOS transistor **62** and a supply voltage source VDD.

In the open-loop branch **B61**, a gate of the PMOS transistor **63** is coupled to the output terminal OUT of the amplifier **60**, and a source of the PMOS transistor **63** is coupled to the output node Noutp. A gate of the NMOS transistor **66** is coupled to the output terminal OUT of the amplifier **61**, a source of the NMOS transistor **66** is coupled to the output node Noutn, and a drain of the NMOS transistor **66** is coupled to a drain of the PMOS transistor **63**. A gate of the NMOS transistor **67** is coupled to the drain of the NMOS transistor **66**, a source of the NMOS transistor **67** is coupled to the signal ground GND, and a drain of the NMOS transistor **67** is coupled to the output node Noutn. The current source **69** is coupled between the source of the PMOS transistor **63** and the supply voltage source VDD.

While operating, a current **I60** and reference voltages Vrefpx and Vrefnx are generated in the closed-loop branch **B60**, and a current **I61** and reference voltages Vrefp and Vrefn are generated in the open-loop branch **B61**. The current **I61** is typically N times the current **I60** for ensuring the driving ability of the reference buffer circuit **6**. Thus, the size of each of the transistors **63**, **66**, and **67** is N times the size of the corresponding one of the transistors **62**, **64**, and **65**. In this embodiment, the size of each transistor can be a respective width-length ratio (W/L). Moreover, the current sources **68** and **69** can be implemented by transistors. For example, if the current sources **68** and **69** are implemented by transistors, the size of the current source **69** is N times of the size of the current source **68**. According to above circuit structure, the reference voltage Vrefp tracks the reference voltage Vrefpx, and the reference voltage Vrefn tracks the reference voltage Vrefnx. Moreover, the NMOS current transistors **65** and **67** act as current sinks.

In the embodiment of FIG. 6, the reference voltages Vrefp and Vrefn are not limited by the voltage differences between the gate and the source of each of the transistors 62, 63, 64, and 66, which are operated in saturation region and coupled to the output terminals OUT of the amplifiers 60 and 61, such that the reference buffer circuit 6 can normally operate under a very low supply voltage provided by the supply voltage source VDD, and the swing between the reference voltages Vrefp and Vrefn can become relatively large. For example, if the current sources 68 and 69 are respectively implemented by MOS transistors, the maximum value of the reference voltage Vrefp is equal to about $(vdd - 1 vds)$, the minimum value of the reference voltage Vrefn is equal to about $1 vds$, and the swing between the reference voltages Vrefp and Vrefn is therefore equal to $(vdd - 2 vds)$, wherein vdd represents the voltage value provided by the supply voltage source VDD, and vds represents the voltage difference between the drain and the source of each of the transistor 67 and the MOS transistor in the current source 69. Moreover, the output impedance of the reference buffer circuit 6 is substantially equal to $1/gm$ so as to rapidly stabilize the reference voltages Vrefp and Vrefn, and the bandwidth of the amplifiers 60 and 61 is not so required, therefore, the power consumption of the reference buffer circuit 6 can be more decreased.

FIG. 7 shows another exemplary embodiment of a differential reference buffer circuit. A differential reference buffer circuit 7 generates reference voltages Vrefp and Vrefn respectively at output nodes Noutp and Noutn and comprises amplifiers 70 and 71, a PMOS source-follower transistor 72, PMOS current transistors 73 and 75, a PMOS driving transistor 74, an NMOS source-follower transistor 76, an NMOS driving transistor 77, and current sources 78 and 79. That is, in the differential reference buffer circuit 7, a closed-loop branch B70 comprises the amplifiers 70 and 71, the PMOS transistors 72 and 73, the NMOS transistor 76, and the current source 78, and an open-loop branch B71 comprises the PMOS transistors 74 and 75, the NMOS transistor 77, and the current source 79. A source of the PMOS transistor 74 is coupled to a drain of the PMOS transistor 75 at an output node Noutp, and a source of the NMOS transistor 77 is coupled to the current source 79 at an output node Noutn.

Referring to FIG. 7, the closed-loop branch B70 generates a current I70 and reference voltages Vrefpx and Vrefnx, and a current I71 and reference voltages Vrefp and Vrefn are generated by the open-loop branch B71. The current I71 is typically N times the current I70 for ensuring the driving ability of the reference buffer circuit 7. Thus, the size of each of the transistors 74, 75, and 77 is N times the size of the corresponding one of the transistors 72, 73, and 76. In this embodiment, the size of each transistor can be a respective width-length ratio (W/L). Moreover, the current sources 78 and 79 can be implemented by transistors. For example, if the current sources 78 and 79 are implemented by transistors, the size of the current source 79 is N times the size of the current source 78. According to above circuit structure, the reference voltage Vrefp tracks the reference voltage Vrefpx, and the reference voltage Vrefn tracks the reference voltage Vrefnx. Moreover, the NMOS current transistors 73 and 75 act as current sources.

In the embodiment of FIG. 7, the reference voltages Vrefp and Vrefn are not limited by the voltage difference between the gate and the source of each of the transistors 72, 74, 76, and 77, which are operated in saturation region and coupled to the output terminals OUT of the amplifiers 70 and 71, such that the reference buffer circuit 7 can normally operate under a very low supply voltage provided by the supply voltage source VDD, and the swing between the reference voltages

Vrefp and Vrefn can become relatively large. Moreover, the output impedance of the reference buffer circuit 7 is substantially equal to $1/gm$ so as to rapidly stabilize the reference voltages Vrefp and Vrefn, and the bandwidth of the amplifiers 70 and 71 is not so required, therefore, the power consumption of the reference buffer circuit 7 can be more decreased.

According to above embodiments, the disclosed reference buffer circuits can normally operate under a low supply voltage without limitation for outputting reference voltages, so that the swing between the reference voltages can be relatively large. Moreover, due to the open-loop branches configured in the reference buffer circuits, the reference buffer circuits can rapidly stabilize the reference voltages Vrefp and Vrefn and have less power consumption.

While the invention has been described by way of example and in terms of the preferred embodiments, it is to be understood that the invention is not limited to the disclosed embodiments. To the contrary, it is intended to cover various modifications and similar arrangements (as would be apparent to those skilled in the art). Therefore, the scope of the appended claims should be accorded the broadest interpretation so as to encompass all such modifications and similar arrangements.

What is claimed is:

1. A reference buffer circuit for providing a reference voltage at an output node, comprising
a closed-loop branch comprising:

an amplifier having a positive input terminal for receiving an input voltage, a negative input terminal, and an output terminal;

a first metal oxide semiconductor transistor having a gate coupled to the output terminal of the amplifier, a source coupled to the negative input terminal of the amplifier, and a drain; and

a second MOS transistor having a gate coupled to the drain of the first MOS transistor, a source coupled to a first voltage source, and a drain coupled to the source of the first MOS transistor; and

an open-loop branch comprising:

a third MOS transistor having a gate coupled to the output terminal of the amplifier, a source coupled to the output node, and a drain.

2. The reference buffer circuit as claimed in claim 1 further comprising a fourth MOS transistor having a gate coupled to the drain of the third MOS transistor, a source coupled to the first voltage source, and a drain coupled to the output node.

3. The reference buffer circuit as claimed in claim 1 further comprising:

a first load unit coupled between the drain of the first MOS transistor and a second voltage source;

a second load unit coupled between the drain of the third MOS transistor and the second voltage source.

4. The reference buffer circuit as claimed in claim 3, wherein the first, second, third, and fourth MOS transistor are NMOS transistors, the first voltage source is arranged to provide a signal ground, and the second voltage source is arranged to provide a supply voltage.

5. The reference buffer circuit as claimed in claim 3, wherein the first, second, third, and fourth MOS transistor are PMOS transistors, the first voltage source is arranged to provide a supply voltage, and the second voltage source is arranged to provide a signal ground.

6. The reference buffer circuit as claimed in claim 1, wherein a current amount flowing through the open-loop branch is N times a current amount flowing through the closed-loop branch.

7. A reference buffer circuit, comprising
a closed-loop branch comprising:

9

an amplifier for receiving an input voltage; a source-follower transistor having a gate coupled to an output of the amplifier and a first terminal coupled to a negative input terminals of the amplifier; and a first current transistor coupled to the first terminal of the source-follower transistor in series and having a gate coupled to a second terminal of the source-follower transistor; and an open-loop branch comprising:

10 a driving transistor having a gate coupled to the output terminal of the amplifier and a first terminal for providing a reference voltage; and a second current transistor coupled to the first terminal of the driving transistor in series and having a gate coupled to a second terminal of the driving transistor.

15 8. The reference buffer circuit as claimed in claim 7, wherein a current amount flowing through the open-loop branch is N times a current amount flowing through the closed-loop branch.

9. The reference buffer circuit as claimed in claim 7, 20 wherein when the source-follower transistor and the driving transistor are PMOS transistors, the first and second current transistors act as current sources; when the source-follower transistor and the driving transistor are NMOS transistors, the first and second current transistors act as current sinks.

10. A reference buffer circuit for providing a first reference voltage at a first output node and a second reference voltage at a second output node, comprising:

a closed-loop branch comprising:

15 a first amplifier having a positive input terminal for receiving a first input voltage, a negative input terminal, and an output terminal;

20 a second amplifier having a positive input terminal for receiving a second input voltage, a negative input terminal, and an output terminal;

25 a first metal oxide semiconductor transistor having a gate coupled to the output terminal of the first amplifier, a source coupled to the negative input terminal of the amplifier, and a drain;

30 a second MOS transistor having a gate coupled to the output terminal of the second amplifier, a source coupled to the negative input terminal of the amplifier, and a drain coupled to the drain of the first MOS transistor; and

35 a third MOS transistor having a gate coupled to the drain of the second MOS transistor, a source coupled to a first voltage source, and a drain coupled to the source of the second MOS transistor; and

40 an open-loop branch comprising:

45 a fourth MOS transistor having a gate coupled to the output terminal of the first amplifier, a source coupled to the first output node, and a drain; and

50 a fifth MOS transistor having a gate coupled to the output terminal of the second amplifier, a source coupled to the second output node, and a drain coupled to the drain of the fourth MOS transistor.

11. The reference buffer circuit as claimed in claim 10, 55 wherein a current amount flowing through the open-loop branch is N times a current amount flowing through the closed-loop branch.

12. The reference buffer circuit as claimed in claim 10 further comprising a first current source coupled between the source of the first MOS transistor and a second voltage source.

13. The reference buffer circuit as claimed in claim 12 60 further comprising:

10

a sixth MOS transistor having a gate coupled to the drain of the fifth MOS transistor, a source coupled to the first voltage source, and a drain coupled to the second output node; and

a second current source coupled between the source of the fourth MOS transistor and the second voltage source.

14. The reference buffer circuit as claimed in claim 13, wherein the first and fourth MOS transistors are NMOS transistors, the second, third, fifth, and sixth MOS transistor are PMOS transistors, the first voltage source is arranged to provide a supply voltage, and the second voltage source is arranged to provide a signal ground.

15. The reference buffer circuit as claimed in claim 13, wherein the first and fourth MOS transistors are PMOS transistors, the second, third, fifth, and sixth MOS transistor are NMOS transistors, the first voltage source is arranged to provide a signal ground, and the second voltage source is arranged to provide a supply voltage.

16. A reference buffer circuit:

a closed-loop branch comprising:

15 a first amplifier for receiving a first input voltage;

20 a second amplifier for receiving a second input voltage;

25 a first source-follower transistor having a gate coupled to an output terminal of the first amplifier and a first terminal coupled to a negative input terminal of the amplifier;

a second source-follower transistor having a gate coupled to the output terminal of the second amplifier, and a first terminal coupled to the negative input terminal of the second amplifier, and a second terminal coupled to a second terminal of the first source-follower transistor; and

30 a first current transistor coupled to the first terminal of the second source-follower transistor in series and having a gate coupled to the second terminal of the second source-follower transistor; and

35 an open-loop branch comprising:

40 a first driving transistor having a gate coupled to the output terminal of the first amplifier and a first terminal for providing a first reference voltage;

45 a second driving transistor having a gate coupled to the output terminal of the second amplifier, a first terminal for providing a second reference voltage, and a second terminal coupled to a second terminal of the first driving transistor; and

50 a second current transistor coupled to the first terminal of the second driving transistor in series and having a gate coupled to the second terminal of the second driving transistor.

17. The reference buffer circuit as claimed in claim 16, wherein when the first source-follower transistor and the first driving transistor are PMOS transistors and the second source-follower transistor and the second driving transistor are NMOS transistors, the first and second current transistors act as current sinks; when the first source-follower transistor and the first driving transistor are NMOS transistors and the second source-follower transistor and the second driving transistor are PMOS transistors, the first and second current transistors act as current sources.

18. The reference buffer circuit as claimed in claim 16, 60 wherein a current amount flowing through the open-loop branch is N times a current amount flowing through the closed-loop branch.
